UNITED STATES PATENT OFFICE.

OSCAR E. SCHAEFER, OF ST. LOUIS, MISSOURI.

CHECK-BOOK AND WRAPPER FOR THE STUBS THEREOF.

1,126,878.

Specification of Letters Patent.

Patented Feb. 2, 1915.

Application filed November 22, 1913. Serial No. 802,392.

To all whom it may concern:

Be it known that I, OSCAR E. SCHAEFER, a citizen of the United States, and a resident of the city of St. Louis, and State of Missouri, have invented a new and useful Improvement in Check-Books and Wrappers for the Stubs Thereof, of which the following is a specification.

My invention relates to check books and the like, and has for its principal objects to provide for the re-filling of the permanent cover and for wrapping the stubs after their removal from the permanent cover.

The invention consists principally in providing stubs with means for temporarily securing the checks in the permanent cover and with the same or a different means adapted to serve as a wrapper for the stubs upon the removal of the body portions of the checks therefrom.

In the accompanying drawing, which forms part of this specification, and wherein like symbols refer to like parts wherever they occur,—Figure 1 is a perspective view of a check book embodying my invention. Fig. 2 is a perspective view of the pad of stubs removed from the permanent cover, and with the wrapping flap opened out into the position that it occupies prior to the removal of the bodies of the checks. Fig. 3 is a perspective view of the pad of stubs with the wrapping flap serving as a cover therefor. Fig. 4 is an enlarged detail sectional view showing the wrapping flap seated in the pocket of the permanent book cover.

The construction illustrated in the drawings comprises a permanent check book cover 1, which has a pocket 2 formed on the inner side of one of its members, this pocket 2 being formed in the usual manner by spacing the lining 3 from the body portion of the cover. The checks are of the usual form consisting of a body member 4 and a stub member 5 separated by a line of perforations 6. Usually, a plurality of checks are printed on a single sheet, with their body portions separated by lines of perforations 7. These checks are bound or fastened together near the margin of the stubs farthest from the body of the checks into blocks or pads. In the present construction, the under side of the pad has a strip 8 of material, such as cloth, secured near said margin and of proper width to serve as a wrapper for the stubs, as hereinafter described. This

strip of material is preferably secured to the pad as follows: The marginal portion of the strip is folded or doubled back, and the marginal portion of the block or pad is inserted between the re-doubled portion 9 (at its bottom) and the extreme marginal portion 10 of the strip, which is folded over the top marginal portion of the pad: and the stub and the strip are then fastened together by means of staples or eyelets 11. The body portion of the cloth strip is then folded underneath the pad in a flat position, in which position it is adapted to enter and coöperate with the pocket 2 provided therefor in the permanent cover and thus constitute a separable means for securing the pad in place.

The strip is creased at 12 opposite the line 6 of perforations separating the stubs from the bodies of the checks, and also along another line 13 parallel with said first line of creasing and at a distance therefrom approximately equal to the thickness of the pad. From this last-mentioned crease to the free outer edge 14 of the strip of cloth, the distance is such that the free marginal portion 15 of said strip can be made to overlap that portion 10 of the strip secured above the pad. In order to facilitate the tucking of the free margin 15 under the secured margin 10 and to make a neater cover, it is desirable to cut away the corner portions of the free end of the strip, as indicated at 16 in the drawings.

By the arrangement above set forth, the strip of cloth serves as a permanent wrapper and protector for the stubs after the removal of the bodies of the checks therefrom. In order to make such covers more valuable, it is desirable to provide thereon spaces for the numbers and dates of the initial and final checks, said spaces having suitable printed indications of their intended use, as shown in Fig. 3. Thus, while the stubs are amply protected by their wrapper, they are susceptible of ready search and accessible to inspection.

While I have described the wrapping strip as adapted to coöperate with the pocket in the permanent cover, it is to be noted that this function is a special one and that the pad can be otherwise secured to the permanent cover. For instance, a common form of permanent cover is equipped with studs adapted to enter eyelets in the pad; and my invention is adapted for use with

this type of permanent cover by reason of the pad being fastened with such eyelets. In this case, it is necessary to perforate the portion of the cloth strip in alignment with the eyelet. The use of the wrapping flap as a securing means is, however, preferable, as it is less expensive and as it permits the stubs to be turned back for use in making indorsements thereon and for other purposes.

Obviously, my invention is not restricted to use with check books, as it is equally applicable to other books and devices whose use leaves a block of stubs. Obviously, also, the device admits of variations of detail without departing from the invention. Thus, while I have specified "cloth" as the material for the wrapper strip, it is obvious that any suitable material may be substituted therefor; in fact, that tag board covered with cloth is preferable. It is also obvious that instead of having the free margin of the wrapper strip tucked into the pocket formed by the secured margin thereof, such free end might be gummed to secure it and guard against unauthorized inspection of the stubs.

What I claim as my invention and desire to secure by Letters Patent is:

- 30 1. A pad of sheets comprising stub portions and body portions separable therefrom, said stub portions being secured along the margin farthest from the body portions, and a strip adapted to constitute a wrapper for the stubs when the body portions are removed therefrom, said strip being secured to the stub portion of said pad and being long enough to incase the stub portions after the body portions are separated therefrom.
- 35 2. A pad of sheets comprising stub portions and body portions separable therefrom and secured together along the margin farthest from the body portions, said pad hav-

ing a pocket on the top thereof, and a wrapper secured on the under side near said margin and having its free end adapted to enter and coöperate with said pocket, said wrapper being of proper length to reach around the free ends of said stub portions after removal of the body portions and let its free end enter said pocket.

3. A pad of sheets comprising stub portions and body portions separable therefrom and secured together along the margin farthest from the body portions, said pad having a wrapper strip comprising a marginal portion on top of the pad secured to said pad at separated points adjacent to the secured margins of the stub portions whereby the portion between said points forms a pocket on top of said pad, a folded securing portion along the lower secured margin of said pad and a body portion which extends under said folded portion and has its free end adapted to coöperate with said pocket upon the removal of the body portions of the sheets, said body portion of said wrapper strip being of proper length to extend around the free ends of said stubs and let the end of said wrapper strip enter said pocket.

4. The combination with a permanent book cover having a pocket therein of a pad of sheets comprising stub portions and a strip of tag board or like material inserted in said pocket, said strip being of sufficient length to incase the stub portions of said pad, whereby said strip is adapted to serve as a wrapper for the stubs upon their removal from said book cover.

Signed at St. Louis, Mo., this 19th day of November, 1913.

OSCAR E. SCHAEFER.
